UNITED STATES PATENT OFFICE.

HENRY WEBER, OF CHICAGO, ILLINOIS, ASSIGNOR TO LATHAM MACHINERY COMPANY, OF CHICAGO, ILLINOIS, A CORPORATION OF ILLINOIS.

STAPLING-MACHINE.

1,177,074.

Specification of Letters Patent. Patented Mar. 28, 1916.

Application filed April 8, 1915. Serial No. 19,891.

To all whom it may concern:

Be it known that I, HENRY WEBER, a citizen of the United States, residing in Chicago, in the county of Cook and State of Illinois, have invented certain new and useful Improvements in Stapling-Machines, of which the following is a specification.

This invention relates to a stapling machine designed especially for use in constructing containers made of card-board or other similar material, and for fastening the closures on such containers. It may, of course, be used for other purposes in which comparatively thin material is to be fastened.

The invention consists substantially in the combination and arrangement hereinafter described, illustrated in the accompanying drawings, and more particularly set forth in the appended claims.

In the drawings—Figure 1 is a fragmentary front elevation of a stapling machine embodying my invention. Fig. 2 is a top plan view of such a machine. Fig. 3 is a fragmentary vertical sectional view showing the way in which the work is presented to the stapling head. Fig. 4 is a perspective view with parts broken away, showing one form of container for which the present invention is especially adapted.

In the drawings, the numeral 1 represents a standard or support for the machine embodying the present invention. The base for the support 1 is not shown, but the support carries at its upper end two laterally projecting arms 2 and 3, spaced one above the other. The arm 2 carries at its extremity a stapling head 3, of well-known construction, adapted to form staples from a continuous wire and force them into the material to be stapled. Stapling heads for this purpose are well known in the art, and it is not necessary for the purpose of this application to show or describe the detailed construction of such a head. It is sufficient to say that the mechanism contained in the stapling head is driven from a pulley wheel 4, and that the staples, after they are formed, are forced upwardly from the upper central portion of the extension 5 carried at the upper part of the stapling head. The wire 6, from which the staples are formed, is carried on a spool 7 mounted on the standard 1. It should be noted that the head 3 is located in an inverted position, so that

the staples are forced upwardly instead of downwardly, as is the usual method of operation of stapling machines. Mounted on a pivot 8 carried on lugs 9 and 10 on the standard 1 is a work table 11. This table 60 is free to swing in a horizontal plane upon 8 as a pivot and when in operating position is supported by a member 12 carried by the arm 2 which supports the head 3. The table is partially cut away, as at 13, to leave an 65 open space above the portion 5 on the stapling head to permit the portion 5 to cooperate with work supported on top of the table.

Adjustably mounted on the upper surface 70 of the table is an angle-bar 14 which is held in position on the table by pins 15 passing through openings in the angle-bar and adapted to enter any one of a series of holes 16 in the table top. The bar 14 acts as a 75 gage to limit the position of the work, as will be explained. Also mounted on the top of the table is a pair of stops 17 adapted to be adjustably held in position by pins 18 which enter openings 19 in the table top. 80 The stops 18 have inwardly beveled or sloping surfaces 20 adapted to cooperate with a cylindrical container to hold it in position, as is indicated in Fig. 1. As is apparent, these stops may be adjusted to accommodate 85 different sized cylinders. The upper arm 3 carries at its extremity a downwardly bent portion 21 on which is mounted a clench or anvil member 22 which extends forwardly from the projection 21 over the part 5 of 90 the stapling head into position to be struck by the ends of staples that are forced upwardly by the stapling head, and thus bend over the ends of the staples and clench them in the work that has been stapled. Adjustably mounted on the clencher 22 by screws 23 is an L-shaped gage 24 carrying a laterally projecting arm 25. The arm 25 is slotted as at 26, and a forwardly projecting pin 27 is mounted to slide in the slot 26. A 100 thumb nut 28 is screwed onto the end of the pin 27 to hold the pin in adjusted position. Graduations 29 are formed on the upper surface of the arm 25 to assist in properly locating the pin 27.

In Fig. 4 is shown one form of container in connection with which the present stapling machine is used. In packaging material, such as coffee, beans, sugar, etc., in a container of this character, the cylindrical 105

110

portion 30 of the container is first formed of very heavy fibrous material. The container itself may be as large as a foot and a half in diameter, and the material of which the cylinder 30 is formed will be approximately 5 from $\frac{1}{8}$ " to $\frac{1}{4}$ " in thickness. After the cylinder 30 has been formed, one of the circular rings 31 of similar material to that from which the cylinder 30 is formed, is secured 10 in one end of the cylinder, the edge of the ring 31 being flush with the end of the cylinder. This ring is fastened in the cylinder by placing the cylinder with the ring in position upon the work table 11 between the 15 guides 17 and resting against these guides as shown in Fig. 1. The gage 14 is adjusted to the proper position to permit the end of the cylinder 30 to extend the proper distance between the parts 5 and 22 to properly position the staple relative to the edges of the ring 31. The member 24 is adjusted on the bolts 23 to bring the finger 27 in position to extend slightly into the open end of the cylinder. The finger 27 is then adjusted 20 longitudinally of the arm 25 to a position where it is spaced from the clencher 22 a distance approximately equal to the distance that it is desired to have the staples spaced from one another circumferentially about 25 the ring 31. The machine is then operated and a staple is forced upwardly by the head 3 into and through the cylinder 30 and ring 31 and is clenched by the member 22 on the upper or inner surface of the ring 31. The 30 cylinder is then rotated upon the table top in a counter-clockwise direction as viewed in Fig. 1 until the staple that has already been placed is brought opposite the finger 27. The machine is then operated a second time 35 and another staple placed in position. This operation is repeated until staples have been equally spaced about the entire periphery of the cylinder. The container is then removed from the machine and placed upon 40 end with the ring 31 downward. A circular disk 32, of a diameter equal to that of the interior of the cylinder 30 is then placed within the cylinder and allowed to rest against the inner edge of the ring 31 that has 45 been stapled in position. This disk 32 now forms the bottom of a cylindrical container which is as yet open at the top. The container is then filled with whatever material it is desired to place within it, a space being 50 left at the top equal to the width of a ring 31, and the thickness of a disk 32. A second disk is then placed upon top of the material in the container and a second ring 31 placed 55 above the disk within the end of the cylinder, and the edge of the ring and end of the cylinder brought to a position where they are flush with one another. The operator then 60 holds the container with his fingers in position to retain the ring 31 in place, and places 65 the filled cylinder upon the table 11 again,

but this time with the other end in position to be operated upon by the stapling mechanism. It is in stapling this last ring in position, after the container has been filled, that the present machine is particularly advantageous. Since staples are inserted from below, the entire weight of the filled container may rest upon the table 11, and all that is necessary for the operator to do is to hold the ring 31 in place until one or two 70 staples have been inserted, and then to rotate the cylinder from one position to the next after each stapling operation.

While I have shown, by way of illustration, the stapling machine as used in connection with a cylindrical container, it, of course, is understood that the machine may be used as well in connection with a variety of articles, such, for instance, as for stapling the bottom and cover of a rectangular container, or for stapling various articles that will readily suggest themselves to those skilled in the art, and it is distinctly understood that I do not wish to confine myself to any particular form of work upon which 85 the machine is operated.

I claim:

1. In a device of the character described, a table having an opening, angular stops carried upon the upper surface of said table, 95 with their inclined surfaces facing one another, a stapling head positioned beneath said table and adapted to force staples upwardly through said opening in said table, a clenching anvil supported above said stapling head, a slotted gage support carried by said clenching anvil, and a pin adjustably carried in said slotted support to enable the operator to properly space the staples in the work carried upon said table. 100

2. In a device of the character described, a support, a pair of laterally extending arms carried by said support positioned one above the other, a stapling head carried by the lower of said arms and adapted to force staples upwardly from the upper portion thereof, a staple clenching anvil carried by the upper one of said arms and extending laterally therefrom to a position to coöperate with said stapling head, a table pivoted to said support intermediate of said arms and having an opening therein adapted to be swung into position over said stapling head, a stationary member adapted to support said table when in said position, and angular stops located upon the upper surface of said table for holding hollow cylindrical work placed upon said table in position to receive said clenching anvil on the interior thereof to coöperate with said stapling head. 115

3. In a device for fastening closures in the end of cylindrical containers, a table provided with an opening and with stops adapted to lie along the elements of a cylindrical container to prevent said container from 120

rolling upon said table, a stapling head positioned below said table and adapted to force staples upwardly through the opening in said table into said cylindrical container 5 from the outer surface thereof, and a staple clenching head adapted to enter the interior of said cylindrical container and clench said staples on the interior side of said cylindrical container.

10 4. In a device for fastening a ring to the interior of a cylindrical container, a table adapted to support said container and having stops for preventing said container from rolling upon said table, a stapling head positioned beneath said table and adapted to force the staples upwardly into the container supported upon said table, and a staple clenching head having a free end adapted to enter the interior of said cylindrical container and clench the staples that are forced therein.

15 5. In a device of the character described, a support, a pair of laterally extending arms carried by said support one above the other, a pivoted table carried by said support intermediate said arms and having an opening therethrough, a stapling head carried by the lower of said arms and positioned beneath said opening in said table, a clenching anvil carried by the upper of said arms and positioned above said stapling head, a pair of angular stops carried by the upper surface of said table in position to coöperate with a cylindrical body carried upon said table above said opening therein and to permit rotation of said body without lateral movement thereof, and an adjustable gage mounted upon said staple clenching anvil

to enable the operator to properly position the staples in said cylindrical work.

6. In a machine for stapling interior hoops in cylindrical containers, an upright standard, lateral arms, one above the other, projecting in the same direction from said standard, a stapling head carried by the lower of said arms and arranged to force staples upwardly from the upper portion thereof, a clencher anvil projecting laterally from the upper of said arms to a position over said head, a table carried by said standard intermediately of said arms and having an opening therein at one edge thereof in alinement with said stapling head and said clencher anvil, stop blocks carried on said table on opposite sides of said opening and normal to the plane of said arms, for holding a cylindrical container in alinement with said stapling head and said clencher anvil, a gage adjustably mounted on said table and extending across said opening in a direction at right angles to said stop blocks for positioning said cylindrical container longitudinally thereof upon said table, and an indicator finger carried by said clencher anvil and adjustable laterally and longitudinally thereof for assisting the operator in spacing staples as they are driven in said cylindrical container.

In testimony whereof I have signed my name to this specification, in the presence 70 of two subscribing witnesses, on this 3rd day of April, A. D. 1915.

HENRY WEBER.
